DESIGN FOR A COMBINED SERVING BAR AND GUARD PARTITION THEREFOR

Jack Stark, Edgemere, N. Y., assignor of one-third to Maurice B. Solomon and one-third to Enos Chatrand, both of New York, N. Y.

Application September 19, 1941, Serial No. 103,413
Term of patent 3½ years

(Cl. D80—2)

To all whom it may concern:

Be it known that I, Jack Stark, a citizen of the United States, residing at Edgemere, in the county of Queens and State of New York, have invented a new, original, and ornamental Design for a Combined Serving Bar and Guard Partition Therefor, of which the following is a specification, reference being made to the accompanying drawing, forming a part thereof.

Fig. 1 is a top plan view of a combined serving bar and guard partition therefor embodying my new design.

Fig. 2 is a partial side elevational view of the same, and

Fig. 3 is a sectional view taken through line 3—3 of Fig. 1.

The essential features of my design are shown in full lines.

I claim:

The ornamental design for a combined serving bar and guard partition therefor, substantially as shown and described.

JACK STARK.
